US0D1113010S

(12) **United States Design Patent** (10) **Patent No.:** **US D1,113,010 S**
(45) **Date of Patent:** **** Feb. 10, 2026**

(54) **VACUUM CLEANER**

(71) Applicant: **Liangjun Chen**, Dongguan (CN)

(72) Inventor: **Liangjun Chen**, Dongguan (CN)

(**) Term: **15 Years**

(21) Appl. No.: **29/951,616**

(22) Filed: **Jul. 10, 2024**

(51) LOC (15) Cl. **15-05**

(52) U.S. Cl.

USPC **D32/18**

(58) **Field of Classification Search**

(57) **CLAIM**

The ornamental design for a vacuum cleaner as shown and described.

DESCRIPTION

FIG. 1 is a perspective view of a vacuum cleaner showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dash-dash broken lines in the drawings depict portions of the vacuum cleaner that form no part of the claimed design.

1 Claim, 8 Drawing Sheets
